CLAIM

The ornamental design for a television receiver, as shown and described.

DESCRIPTION

FIG. 1 is a front perspective view of the television receiver showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a back perspective view thereof;

FIG. 9 is a reference view showing the state of use that the front display part has been rotated 90 degrees; and,

FIG. 10 is a reference view showing the state of use that the angle of the front display has been adjusted.
